TEMPERATURE CONTROL MEANS FOR SUGAR MINGLER.

Charles A. Olcott, West Milford, N. J.

Application December 10, 1951, Serial No. 260,792

6 Claims. (Cl. 127—17)

This invention relates to sugar manufacturing and more specifically to improvements in apparatus for the heating of the massecuite prior to its processing in a battery of centrifugals.

It is an object of the present invention to make more uniform the temperature of mixtures applied to the various centrifugals in a battery of such machines.

In the sugar refining art, it is the practice to heat the massecuite prior to its application to the centrifugal machines to ensure the proper temperature for the best results. Frequently the massecuite is heated by a long rotating coil in a mixer tank overlying a battery of centrifugals, say ten or twelve, for example. With such a long coil, the problem arises of maintaining approximately uniform heating in the mixture so that massecuite of substantially the same temperature is applied to each centrifugal in the battery. Some such installations involving a long mixer have operated with a substantial difference in temperature between the massecuite at one end and that at the other because the circulating water in the mixer coil cannot give up heat to the mixture in the tank without becoming cooler and the temperature thus becomes progressively lower along the length of the coil.

Various means have been tried in the past in an attempt to solve this problem but they have not been entirely satisfactory. One attempted solution to the problem has been to feed the hot water into the rotating coil from both ends and to take off the cooled water from the middle but it has been found that a rotary joint with water on one side and massecuite on the other is very unsatisfactory. Another way suggested to solve the problem is to force the heating water so fast through the mixer that only a small drop in temperature results. This theory, however, lacks perfection in practice for two reasons. First, it has been found that the viscosity of molasses doubles with every 9 degree drop in temperature so that even a relatively small decrease in temperature—say 4½ degrees—results in an increase of approximately 50% in molasses viscosity. This means that, on a given operating cycle, the dry charge of sugar at the cool end contains 50% more molasses than the dry charge at the hot end and this difference is very detrimental in the process. Second, it is often not possible to increase the flow of circulating water because it is not practicable to increase the size of the pipes or to change the pump to increase the water velocity.

Still another way of solving this problem is to regulate the respective purging times of the centrifugals in the group so that each operates on a cycle which will properly purge the massecuite. In other words, the centrifugal receiving a warmer mixture requires a smaller purging period than one receiving a cooler mixture. However, there is a decided advantage in operating all of the centrifugals in the group in the same cycle of operation.

In accordance with the present invention, a relatively even distribution of temperature is maintained in the

2

mixing tank and all outlets therefrom receive heated material at the same temperature by causing the heating water to flow in one direction through the rotating coil for a predetermined interval of time and then reversing the water flow for a like interval of time. The correct time intervals can be determined either by timing controls or by thermostatic means. With the present invention, all centrifugals in the group receive massecuite at the same temperature so all start and end their purging cycles at the same times.

In a specific exemplary embodiment of the invention, a 4-way valve is employed between the water pump and the two ends of a coil section. In one position of the valve, the water enters one end of the coil section and flows out of the opposite end of the section while in the second position of the valve the water enters the latter end of the coil section and leaves the former end. Thermostatic or timer means are provided to operate the valve periodically during the process from one position to the other.

The invention will be more readily understood by referring to the following description taken in connection with the accompanying drawings forming a part thereof, in which:

Fig. 1 is a schematic elevation view, partly in cross-section, of a multi-unit centrifugal installation in accordance with the invention including apparatus for heating the sugar bearing material before its application to the centrifugals and having one form of temperature responsive valve control means;

Fig. 2 is a schematic view of a portion of the apparatus of Fig. 1 showing the 4-way valve position for one direction of liquid flow through the coil and including another form of temperature responsive valve control means;

Fig. 3 is a schematic view of the apparatus of Fig. 2 showing the position of the 4-way valve for the opposite direction of liquid flow; and

Fig. 4 is a partial schematic view of time responsive valve control apparatus for the 4-way valve.

For a detailed description of the invention, a more specific reference is now made to the drawings. Fig. 1 shows, by way of example for purposes of illustration, a multi-unit sugar centrifugal installation 10 embodying a material heating arrangement in accordance with the invention. The installation 10 includes a battery of centrifugals 11 of any suitable type used for drying sugar bearing materials. By way of example, twelve centrifugals have been shown but obviously more or less than this number can be used. Overlying the centrifugals is a mixing tank 12 containing a hollow rotary coil 13 containing terminals 14 and 15 through which heating fluid (usually hot water) is admitted and removed from the coil. Any suitable coil can be used, satisfactory examples being described in Patent 2,055,778, issued September 29, 1936, to G. E. Stevens and in Patent 2,178,805, issued November 7, 1939, to Charles A. Olcott. The coil is rotated by any suitable means (not shown). Suitable outlets or conduits 16 connect the tank 12 with the centrifugals 11. Above the mixing tank 12 is a battery of crystallizers 17 in which the sugar grains are crystallized from the syrup obtained from the low grade sugar-bearing mother liquors by boiling in vacuum pans, as is well known in the sugar refining art.

The heating water is circulated through a sealed loop into which more water can be added as desired. The water is caused to be forced through the loop by pump 18 which is in a series path including a heater 19, a first path through the 4-way valve 20, the coil 13, and a second path through the 4-way valve. Reference will now be made to Figs. 2 and 3 in addition to Fig. 1. Fig. 2 shows a first position of the 4-way valve by means

of which the heating water enters the coil 13 at its left hand terminal and leaves it at the right terminal 15 while Fig. 3 shows the second position of the valve whereby the heating water enters the right terminal 15 and leaves through the left one 14. Arrows have been used in the drawing to indicate the directions of flow for the two valve positions.

In the practice of the present invention, the heating water is circulated through the coil from left to right for a predetermined period of time (for example, about one minute). The valve element in the 4-way valve 20 is then rotated 90 degrees from the first position (Fig. 2) to the second position (Fig. 3) and the water is passed through the coil in the opposite direction (that is, from right to left) for a second predetermined period of time, which preferably is the same as the first period of time but which may be made different if desired. By this means, the temperature of the material at each outlet 16 is the same as at all others. The valve 20 may be turned by hand but preferably automatic means are used to control the valve position. By way of example, three systems of automatic valve control have been shown in the drawings. The first two of these, shown in Figs. 1 and 2, respectively, are based on temperature changes while the third (Fig. 4) is time responsive.

The temperature responsive means of Fig. 1 comprises a thermocouple 21 positioned at one end of the mixing tank 12. When the temperature of the massecuite 22 reaches a predetermined value, the member 21 causes a circuit including source of potential 23 and the coil of solenoid 24 to close, thus actuating the solenoid armature to change the position of the valve. When the temperature reaches a second predetermined value the electrical circuit is opened and the valve 20 is operated to its original position. By way of example, let it be assumed that satisfactory mixing can be accomplished if the mixer coil heating fluid averages 160 degrees F. If the water is heated to 165 degrees F. in the heater 19, the temperature at the input end is approximately this value and is at a much lower figure, say 155 degrees, at the exit end, thus averaging 160 degrees at the center of the coil.

A second temperature responsive means is shown in Figs. 2 and 3. This arrangement includes two elements 30 and 31 placed in the massecuite at respectively opposite ends of the mixing tank 12 and temperature-differential responsive control means 32 for energizing the solenoid 24 to actuate the valve 20 (the valve actuating means being represented schematically by the dash-dot connection 33) when the temperature of the element 30 at the left hand end exceeds the temperature of the element 31 by a predetermined amount, say 1 or 2 degrees. Controls responsive to temperature differentials are well known and available commercially so their detailed description herein is unnecessary.

Fig. 4 shows schematically a time-responsive means for controlling the valve 20 to periodically change the direction of flow in order to maintain a constant average temperature in the mixer. This embodiment includes a rotary timer 40 having contacts at appropriate places to energize and deenergize periodically one or more times each rotation the solenoid 24 to actuate the valve 20. Many suitable timers are available commercially. By way of example, let it be assumed that the mixer holds about 4 charges for each centrifugal and that each charge takes about 10 minutes to dry. For this example, there would be a change of massecuite about every 40 minutes. Very satisfactory results can be obtained if the flow of heating water is reversed every 20 minutes by the timer. However, it is desirable to have this reversal adjustable both as to frequency and to the length of time that the water flows in one direction as compared to the other. An example of when unequal time periods are desirable occurs when the inflow of cold massecuite is more pronounced at one end (say, the left) of the mixer than

the other so more heat would be desired at the left end than at the other. Under these conditions, there might be 30 minutes of flow in the direction of Fig. 3 to compensate for the greatly cooling effect of incoming magma at the left hand end as compared with the right hand end.

Obviously, various changes can be made in the embodiments disclosed without departing from the spirit or letter of the invention. By way of example, pneumatic means can be used instead of solenoids for controlling the 4-way valve.

What is claimed is:

1. In combination, an elongated mixing tank for the temperature conditioning of sugar massecuite and the like, a relatively long, hollow, rotary stirring means or coil adapted to be rotated in said tank, a plurality of outlets for said tank spaced along the length thereof, means for applying temperature conditioning liquid to said coil and for removing it therefrom, and means for 15 maintaining the temperature of the massecuite at each of said outlets substantially the same as that at all other outlets, said last-mentioned means comprising valve means for periodically reversing the direction of said liquid flow through said coil during the temperature conditioning process.

2. In combination, an elongated mixing tank for the temperature conditioning of sugar massecuite and the like, a relatively long, hollow, rotary stirring means or coil adapted to be rotated in said tank, a plurality of outlets for said tank spaced along the length thereof, means for applying temperature conditioning liquid to said coil and for removing it therefrom, and means for maintaining the temperature of the massecuite at each of said outlets substantially the same as that at all other outlets, said last-mentioned means comprising valve means for periodically reversing the direction of said liquid flow through said coil during the temperature conditioning process and means responsive to the temperature of the massecuite for controlling the flow-direction reversal times.

3. In combination, an elongated mixing tank for the temperature conditioning of sugar massecuite and the like, a relatively long, hollow, rotary stirring means or coil adapted to be rotated in said tank, a plurality of outlets for said tank spaced along the length thereof, means for applying temperature conditioning liquid to said coil and for removing it therefrom, and means for maintaining the temperature of the massecuite at each of said outlets substantially the same as that at all other outlets, said last-mentioned means comprising valve means for periodically reversing the direction of said liquid flow through said coil during the temperature conditioning process and a timing mechanism for controlling the flow-direction reversal times.

4. In combination, an elongated mixing tank for the temperature conditioning of sugar massecuite and the like, a relatively long, hollow, rotary stirring means or coil adapted to be rotated in said tank, a plurality of outlets for said tank spaced along the length thereof, means for applying temperature conditioning liquid to said coil and for removing it therefrom, and means for maintaining the temperature of the massecuite at each of said outlets substantially the same as that at all other outlets, said last-mentioned means comprising valve means for periodically reversing the direction of said liquid flow through said coil during the temperature conditioning process, said flow reversing means including a 4-way valve.

5. In combination, an elongated mixing tank for the temperature conditioning of sugar massecuite and the like, a relatively long, hollow, rotary stirring means or coil adapted to be rotated in said tank, a plurality of outlets for said tank spaced along the length thereof, means for applying temperature conditioning liquid to said coil and for removing it therefrom, and means for

maintaining the temperature of the massecuite at each of said outlets substantially the same as that at all other outlets, said last-mentioned means comprising valve means for periodically reversing the direction of said liquid flow through said coil during the temperature conditioning process and means responsive to the difference in temperature between the two ends of the mixing tank for controlling the flow-direction reversal times.

6. In combination, an elongated mixing tank for the temperature conditioning of sugar massecuite and the like, a relatively long, hollow, rotary stirring means or coil adapted to be rotated in said tank, a plurality of outlets for said tank spaced along the length thereof, means for applying temperature conditioning liquid to said coil and for removing it therefrom, and means for maintaining the temperature of the massecuite at each of said outlets substantially the same as that at all other outlets, said last-mentioned means comprising valve means for periodically reversing the direction of said liquid flow through said coil during the temperature conditioning process and means responsive to the change in

temperature at one end of the mixing tank for controlling the flow-direction reversal times.
